NOZZLE FOR SUCTION CLEANERS

George N. Edwards, Willoughby, Ohio, assignor to
 The Ohio Rubber Company, Willoughby, Ohio,
 a corporation of Ohio

Application July 17, 1935, Serial No. 31,875

3 Claims. (Cl. 15—158)

This invention relates to nozzles for vacuum cleaners, and has particular reference to a nozzle, including a relatively rigid body member provided with a row of bristles surrounding a suction opening extending therethrough and provided in line with the opening and inside the row of bristles with a soft yieldable extension or cup. Generally also the body member has its outer portion covered with rubber or other soft material to reduce the liability of marring furniture and the like.

Heretofore, the bristle holder, the flexible cup therein, and the soft protector for the margin of the bristle holder have been separately formed and the parts attached together. Additionally, there is required a connector or adapter which is a separate piece secured to the bristle holder and is adapted to receive the end of a tubular member connected to the suction cleaner.

It is the purpose of the present invention to provide a suction nozzle, particularly of the type referred to, which can be produced less expensively and which is generally more satisfactory than the multi-part nozzles used heretofore.

More particularly it is the aim of the invention to form the rigid and the yieldable parts as a unit, thereby avoiding the expense incident to the assembly and attaching of separately formed parts and the disadvantage of accidental separation of the parts in use or otherwise.

In carrying out my invention, I form the rigid body member or bristle holder, the soft cup on the interior of the bristles, and the outer soft covering in one unitary member, as by forming them of hard and soft rubber compositions vulcanized into a single unitary body, each part, however, retaining its relatively hard or relatively soft characteristics, as the case may be. I may also form the adapter or connector, which heretofore has been attached to the body member and makes connection with the suction tube or pipe, integrally with the body member or bristle holder.

The invention may be further briefly summarized as consisting in certain novel details of construction and combinations and arrangements of parts which will be described in the specification and set forth in the appended claims.

In the accompanying sheet of drawings,

Fig. 1 is a view in perspective showing conventionally a vacuum cleaner to which the invention may be applied;

Fig. 2 is a cross-sectional view of one form of nozzle made in accordance with my invention;

Fig. 3 is a plan view of the same;

Fig. 4 is a view similar to Fig. 2 showing a modification;

Fig. 5 is a plan view of Fig. 4 with the adapter removed; and

Figs. 6 and 7 are cross-sectional views of further modified forms of the nozzle.

Referring now to the drawing, 10 represents a vacuum or suction cleaner as a whole which may be of any suitable construction. At 11 I have shown the nozzle to which is attached the flexible hose 12 leading to the cleaner. The nozzle may have any suitable shape or contour, but in Figs. 2 and 3 it is shown round and in Figs. 4 and 5 it is shown elongated.

In Figs. 2 and 3 the nozzle is provided with a body portion 13 having an annular row of flexible bristles 14 which are generally arranged in groups or bundles set into openings of the body 13 and fastened by staples or otherwise. The body member 13 has a central suction opening and in line with this opening there is a soft flexible cup 15 which extends from the body or bristle holder 13 centrally into the space inside the row of bristles and terminates a distance above the free ends of the bristles. Also surrounding the body member or bristle holder is an outer covering 16 of soft yieldable material the purpose of which is to form a cushion to lessen the likelihood of furniture being marred by the manipulation of the nozzle.

To the body member or bristle holder 13 there is usually secured by screws or otherwise an adapter or connector 17 which has a tubular extension adapted to be fitted telescopingly into or over one end of the suction hose 12 or a tube or pipe which is connected thereto. The inner cup 15 in effect forms an extension of the suction line through the body member 13, adapter 17, and the connecting hose to the suction chamber of the vacuum cleaner.

It is a feature of the present invention that the rigid bristle holder or body member 13, the soft inner cup 15, and the soft outer covering 16 are formed as a unit. These parts are preferably formed from hard and soft rubber compositions which are molded and vulcanized together so as to provide a unitary element consisting of the hard or rigid bristle holding body member, the soft flexible cup or extension 15, and the outer soft covering 16. While these parts are preferably formed of rubber, they may be formed of other materials of an equivalent nature which, in the curing operation, are caused to become one unitary piece or structure and

which will retain the desired hard and soft characteristics.

As previously pointed out, the body member or bristle holder of the nozzle may have any suitable shape or contour, such as round, as shown in Figs. 2 and 3, or elongated, as illustrated in Figs. 4 and 5, wherein the body member is designated 18. When an elongated body member is employed, the lower contacting end of the 10 adapter, designated 19 in Figs. 4 and 5, will be correspondingly shaped, as will also the inner soft flexible cup here designated 20, and of course the outer soft covering 16 and the row of bristles 14 will have an elongated contour 15 responding to the shape of the nozzle body member. The soft flexible cup inside the row of bristles may otherwise be variously shaped. For example, in Figs. 2 and 6 the cup 15 is shown flared outwardly from its upper to its lower end, 20 while in Fig. 4 it is shown extending straight downward from the body member of the nozzle. In Fig. 7, the cup, here designated 21, is of bulbous form, being bulged outwardly below the body member and at its lower end being curved 25 inwardly and in this instance upwardly at its free end 21a to form a restricted passage 21b at its lower end. It may be otherwise shaped as may be found desirable.

I find that the unit idea embodied in the construction of the nozzle may be extended to include the adapter which heretofore has been a separate member attached to the body or bristle holder of the nozzle, and this is illustrated in Figs. 6 and 7 wherein the body member 30 and the adapter, here designated 22, are formed in one piece preferably of hard rubber or equivalent material. It will be understood that with all forms of the invention, regardless of the shape or contour of the bristle holder and of the soft 35 inner flexible cup 15, 20, or 21, and regardless of whether the body member and the adapter are formed separately and attached together, as in Figs. 2 and 4, or are formed integrally, as illustrated in Figs. 6 and 7, the unit idea or unitary 40 construction feature of the hard body member, the soft inner cup or extension, and the soft covering 16 is preserved so that the advantages 45

or objects of the invention stated at the beginning of the specification are attained.

While specific shapes have been shown and described and specific materials mentioned, I do not desire to be confined to these details but 5 aim in my claims to cover all modifications which do not involve a departure from the spirit and scope of my invention.

Having thus described my invention, I claim:

1. A nozzle for suction cleaners comprising a 10 rigid tubular body member having a suction opening extending therethrough and provided at its end with a laterally extending marginal flange, bristles mounted on said flange and disposed around the suction opening, and a soft 15 yieldable cup-like member located inside the bristles and forming an extension of the suction opening, said cup-like member being formed integral with said flange and being provided with an opening which merges smoothly with the 20 suction opening of said body member.

2. A nozzle for suction cleaners comprising a rigid tubular body member having a suction opening extending therethrough and provided at its end with a laterally extending marginal flange, 25 bristles mounted on said flange and disposed around the suction opening, and a soft yieldable cup-like member located inside the bristles and forming an extension of the suction opening, said cup-like member being flared and having the 30 small end thereof connected with said flange and provided with an opening which merges smoothly with the suction opening of said body member.

3. A nozzle for suction cleaners comprising a rigid tubular body member having a suction opening extending therethrough and provided at its end with a laterally extending marginal flange, bristles mounted on said flange and disposed around the suction opening, a soft yieldable cup-like member located inside the bristles and forming an extension of the suction opening, said cup-like member being formed integral with said flange and being provided with an opening which merges smoothly with the suction opening of 35 said body member, and a soft yieldable covering 40 formed integral with said flange and extending 45 around the outer edge thereof.

GEORGE N. EDWARDS.
